(57) **CLAIM**

The ornamental design for a chassis plate, as shown and described.

DESCRIPTION

FIG. 1 is a front view of a chassis plate showing our new design.

FIG. 2 is a top view thereof.

FIG. 3 is a bottom view thereof.

FIG. 4 is a left-side view thereof.

FIG. 5 is a right-side view thereof.

FIG. 6 is a rear view thereof.

FIG. 7 is a front left perspective view thereof.

FIG. 8 is a rear left perspective view thereof.

FIG. 9 is a front view thereof showing cross sectional lines indicating the views in FIGS. 10 and 12-18.

FIG. 10 is a cross-sectional view thereof along line 10-10 shown in FIG. 9.

FIG. 11 is a detailed view of the encircled portion 11 shown in FIG. 10.

FIG. 12 is a cross-sectional view thereof along line 12-12 shown in FIG. 9.

FIG. 13 is a cross-sectional view thereof along line 13-13 shown in FIG. 9.

FIG. 14 is a cross-sectional view thereof along line 14-14 shown in FIG. 9.

FIG. 15 is a cross-sectional view thereof along line 15-15 shown in FIG. 9.

FIG. 16 is a cross-sectional view thereof along line 16-16 shown in FIG. 9.

FIG. 17 is a cross-sectional view thereof along line 17-17 shown in FIG. 9; and,

FIG. 18 is a cross-sectional view thereof along line 18-18 shown in FIG. 9.

The short, broken lines showing the remaining portions of the chassis plate illustrate features of the chassis plate that form no part of the claimed design.

(Continued)

The broken lines consisting of dot-dash lines are boundary lines of the chassis plate that show the chassis plate extends to the boundary line, but does not include the boundary line.
